UNITED STATES PATENT OFFICE

HENRY W. O'DOWD, OF JERSEY CITY, NEW JERSEY, ASSIGNOR TO STANDARD GAS EQUIPMENT CORPORATION, A CORPORATION OF MARYLAND

BURNER UNIT FOR GAS HEATING APPARATUS

Application filed November 10, 1926. Serial No. 147,461.

This invention relates to burner units for gas stoves or ranges and for gas heating apparatus in general.

In my prior Patent No. 1,647,712, dated November 1, 1927, there is shown and described a burner equipment for gas ranges and the like, wherein a Bunsen burner member formed with flame ports is combined with a coverplate sustained by said member in spaced relation thereto and provided with secondary air discharge openings through which the flame jets project when the burner is in operation.

The present invention is directed to an improvement upon said burner equipment and has for an object to provide a burner unit which will not only realize the advantages of said prior equipment but also possess advantages peculiar to itself.

The invention consists broadly in locating the flame ports of the burner member so that they may be segregated into groups of individual ports arranged in close contiguity, and in forming the secondary air discharge openings of the cover-plate so that the flame jets from all the ports of a group will be projected through one or a common discharge opening, and this without impairing the integrity of the individual flame jets, and in the same manner and with the same general results as if said flame jets were projected each through its own individual discharge opening in the coverplate.

The burner unit according to this invention has the important advantage, among others, that the flame ports may be greatly increased in number for a given size of burner member and the heating efficiency of the burner unit correspondingly increased. Like the burner unit, also, upon which it is an improvement, it has been found to be remarkably efficient and free from many of the objections of prior constructions, the coverplate not only providing for the proper aeration of the burner flames, but serving in addition to prevent contamination of the secondary air supply by the waste products as well as to guard against back pressure, flame deflection, air currents and other influences which interfere with proper com-

bustion or impair the heating efficiency of the burner.

In order that the invention may be fully understood there will now be described by way of example and with reference to the accompanying drawings, a construction of the apparatus made in accordance with the invention.

In these drawings:

Fig. 1 is a vertical section of a gas range equipped with burner units made in accordance with the invention;

Fig. 2 is a plan view of the range shown in Fig. 1, parts being broken away or omitted to expose the improved burner units;

Fig. 3 is a plan view of the improved burner unit per se, with a portion of the coverplate removed;

Fig. 4 is a sectional elevation taken on the line 4—4 of Fig. 3, looking in the direction of the arrows; and

Fig. 5 is a fragmentary sectional elevation taken on the line 5—5 of Fig. 3, looking in the direction of the arrows.

Referring to the drawings, the Bunsen burner member A therein shown is of the well known star type and has in each of its branch arms a row of nibs A¹ aligned in close contiguity and having orifices through which the gaseous mixture issues and which constitute the flame ports of the burner. Extending forwardly from the burner member is a mixing tube A² provided, as usual, with an air chamber A³ into which the gas is discharged from a nozzle A⁴ under the control of a stop cock or valve A⁵. As best shown in Fig. 3, the central web portion of the burner member is formed with openings A⁶ to allow secondary air to flow upwardly therethrough.

In accordance with the present invention, the Bunsen burner member A is partially enclosed within a coverplate B, which, in this instance, is formed with a depending flange or hood B¹ extending around the outer ends of the branch arms of the burner member. In its lower edge, the flange or hood B¹ is formed with recesses or notches B² engaged with supporting lugs A⁷ cast or otherwise secured to the ends of four of the branch arms of the burner at symmetrically located

points. The coverplate is held in place upon the supporting lugs by means of a cotter pin A⁸ passed through a perforated ear piece A⁹ extended upwardly from the burner member 5 through a centrally located slot B³ in the coverplate. As will be noted, the arrangement of the parts is such that the coverplate B is maintained in spaced relation to the burner member A so as to provide in connection therewith a secondary air chamber C having as its inlet the openings C¹ created between the branch arms as well as the more centrally located openings A⁶ of the burner member. As an outlet for the secondary air 15 chamber C, the coverplate B is formed with a plurality of discharge openings B⁴, one for each of the groups of flame ports presented by the respective arms of the burner member. Preferably and as herein shown, the 20 sides of the discharge openings B⁴ are given a wavy or serrated configuration so as to form a group of alined and closely contiguous open-sided discharge nozzles B⁵ arranged directly above the gas nibs A¹ and disposed 25 in centered relation to the flame ports. In the particular construction shown, the upper ends of the gas nibs are situated below the under face of the coverplate but they might be made longer or shorter, if desired. The 30 main consideration is that, when the burner is in use, the flame jets shall project through the secondary air discharge openings so as to entrain from the chamber C whatever quantity of secondary air is required to support combustion. And in this respect it is 35 pointed out that the serrated sides of the discharge openings, while not meeting to form closures, do direct secondary air to the flames projecting through the discharge nozzles and maintain the integrity of the individual flames, as in keeping them from mushing with each other, and surround each flame 40 with a column or aura of secondary air. 45 Many advantages characterize the foregoing construction. It will be apparent, for example, that the number of flame ports in the burner member for any given space may be increased to any desired extent consistent with proper flame propagation, due to the 50 fact that a single or common secondary air discharge opening serves all of the flame ports of each group. This feature is particularly useful in reducing the size of the flame ports so as correspondingly to reduce the 55 back pressure at the ports and to prevent "popping back", such reduction in the size of the flame ports being compensated for of course by the increase allowed in the number of ports. Moreover, it is to be noted that 60 these advantages do not destroy certain other advantages attending the combination of burner unit and coverplate. For instance, the secondary air is supplied to the burner in substantially pure atmospheric condition 65 and without contamination by the waste

products, being drawn into the interior chamber C through the openings C¹ and A⁶ which are located below the level of the flame ports, and then entrained from the chamber directly by the flame jets as they project 70 through the discharge nozzles B⁵. As matter of fact, the coverplate serves to prevent the secondary air from commingling with the flame jets except through the discharge nozzles. Again, the burner, being protected 75 against the heat of the products of combustion, has less tendency to cause an excessive expansion of the contained gas such as would reduce the entrainment of the primary air. On the other hand, the air pocketed within 80 the coverplate becomes heated by the products of combustion and may therefore be more effectively entrained at the flame ports. In this connection, it may be stated that the discharge openings not only facilitate the 85 proper entrainment of secondary air but also serve to effect a thorough admixture of the gas and air in promoting combustion. Also, the pressure of the products of combustion at the flame ports is reduced to a minimum, thereby lessening the tendency to back 90 pressure and hence more nearly preserving the initial entrainment of primary air. Moreover, the coverplate protects the burner member from contrary air currents or flame 95 deflection or other moving bodies which might otherwise interfere with proper combustion. These and other advantages will be readily appreciated by those skilled in the 100 art. 105

In the preferred construction above described, the discharge openings are shown with serrated sides, but the invention in its broader aspects contemplates other forms of discharge openings. For instance, each discharge opening may be in the form of an even or straight edged slot of a width sufficient to permit the passage therethrough of the flame jets and their auras of secondary air but not so wide as to permit an excess of secondary air to cause the flame jets to mush or lose direction or otherwise to impair the integrity of the flame jets. In such case, the side walls of the slot should preferably converge upwardly so as to produce a better entrainment of the secondary air. Also, it is pointed out that the discharge openings need not be rectilinear, but may follow curved or angular courses corresponding with the alignment of the flame ports of any group. 115

In Figs. 1 and 2 the burner unit is illustrated as embodied in a gas range presenting a cooking top 27 with open grids 28 above the burner units and an underlying combustion chamber 33. The improved burner units (four in the present instance) are located within the combustion chamber in the front and rear portions thereof, being supported upon transverse rods or bars 34 which maintain them the proper distance from the cook- 120

ing top, and the stop cocks or valves A⁵ of the respective units being connected to a common gas supply pipe or manifold 66 situated at the front of the range.

5 The open grids provide the outlets for the products of combustion, and at the front the combustion chamber is provided with a secondary air inlet opening 36 extending approximately the full width thereof and situated at a level below that of the burner units. 10 When the range is in use, therefore, the secondary air, while free to enter the combustion chamber through its inlet 36, is prevented from commingling with the flame jets except 15 through the discharge nozzles B⁵ of the coverplate B, it being noted that the depending flange or hood B¹ of the coverplate acts to direct said air upwardly into the chamber C formed between the burner member and the coverplate. 20 In this way, the secondary air required to support combustion is induced into and entrained from the chamber C under the positive control of the flame jets, thus insuring the proper speed of combustion or 25 flame propagation and allowing the burners to be located as near the cooking top as may be desired without giving rise to the objections so common in the use of the ordinary gas burners.

30 The invention is not, of course, confined to the precise constructions shown and described, nor to any other particular construction by which the same may be carried into effect, as many changes may be made in the details without departing from the main principles of the invention and without sacrificing its chief advantages.

Having thus described my invention, what I claim is:

40 1. A burner unit including, in combination, a Bunsen burner member having a group of aligned individual flame ports arranged in close proximity to each other, and a unitary cover plate sustained above said burner member and having a continuous discharge opening common to all the flame ports and presenting side walls disposed at opposite sides of said ports, said cover plate forming between itself and the burner member a secondary air chamber and having its discharge opening situated in a zone immediately above that of the flame ports, whereby the flame jets entrain secondary air and are discharged therewith through said discharge opening.

55 2. A burner unit including, in combination, a Bunsen burner member having individual flame ports arranged in groups, the ports in each group being aligned with and arranged in close proximity to each other, and a unitary cover plate sustained above said burner member and having a plurality of separate continuous discharge openings, one for each group of flame ports and common to all of the flame ports of that group, each discharge opening presenting side walls disposed at op-

posite sides of said ports, said cover plate forming between itself and the burner member a secondary air chamber and having its discharge openings located in a zone immediately above that of the flame ports, whereby the flame jets entrain secondary air and are discharged therewith through said discharge openings. 70

3. A burner unit including, in combination, a Bunsen burner member having a group of aligned individual flame ports arranged in close proximity to each other, and a cover plate sustained above said burner member and having a continuous discharge opening common to all the flame ports, said cover plate forming between itself and the burner member a secondary air chamber and having its discharge opening situated in a zone immediately adjacent that of the flame ports, and the said discharge opening presenting serrated parallel sides with the serrations on opposite sides in register and forming between them discharge nozzles for the individual flame jets, whereby the flame jets entrain secondary air and are discharged therewith through said discharge nozzles.

4. A burner unit including, in combination, a Bunsen burner member having individual flame ports arranged in groups, the ports in each group being aligned with and arranged in close proximity to each other, and a cover plate sustained above said burner member and having a plurality of separate continuous discharge openings, one for each group of flame ports and common to all of the flame ports of that group, said cover plate forming between itself and the burner member a secondary air chamber and having its discharge openings located in a zone immediately adjacent that of the flame ports, and the said discharge openings each presenting serrated parallel sides with the serrations on opposite sides in register and forming between them discharge nozzles for the individual flame jets, whereby the flame jets entrain secondary air and are discharged therewith through said discharge nozzles. 95 100 105 110

5. In or for a gas range equipped with a cooking top, a burner unit situated below the cooking top and including, in combination, a Bunsen burner member having a group of aligned individual flame ports arranged in close proximity to each other, and a unitary cover plate interposed between the burner member and the cooking top and forming a secondary air space between the burner member and the cover plate and a combustion space between the cover plate and the cooking top, said cover plate being formed with a discharge opening disposed directly above and common to all of the flame ports and presenting side walls disposed at opposite sides of said ports, whereby the flame jets entrain secondary air and are discharged therewith through said discharge opening. 115 120 125 130

6. In or for a gas range equipped with a cooking top, a burner unit situated below the cooking top and including, in combination, a Bunsen burner member having a group
6 of aligned individual flame ports arranged in close proximity to each other, and a cover plate interposed between the burner member and the cooking top and forming a secondary air space between the burner member
10 and the cover plate and a combustion space between the cover plate and the cooking top, said cover plate being formed with a discharge opening disposed directly above and common to all of the flame ports, and said
15 opening presenting serrated parallel sides with the serrations on opposite sides in register and forming between them discharge nozzles for the individual flame jets, whereby the flame jets entrain secondary air and are
20 discharged therewith through said discharge opening.

In testimony whereof, I have affixed my signature hereto.

HENRY W. O'DOWD.
